UNITED STATES PATENT OFFICE

PEARL B. HOWARD, OF BILOXI, MISSISSIPPI

DESIGN FOR A BED QUILT OR SIMILAR ARTICLE

Application filed September 8, 1932. Serial No. 44,775. Term of patent 3½ years.

To all whom it may concern:

Be it known that I, PEARL B. HOWARD, a citizen of the United States of America, residing at Biloxi, in the county of Harrison and State of Mississippi, have invented a new, original, and ornamental Design for a Bed Quilt or Similar Article, of which the following is a specification, reference being had to the accompanying drawing, forming a part thereof,

In the drawing:

The figure is a plan view of one corner of a bed quilt or similar article showing my new design, which design is repeated throughout the entire area of the quilt.

I claim:

The ornamental design for a bed quilt or similar article, as shown and described.

PEARL B. HOWARD. [L.S.]
